UNITED STATES PATENT OFFICE.

HENRY SMOYER, WILLIAM H. CUMMING, AND HERBERT W. THIELE, OF NORTH TONAWANDA, NEW YORK.

BURNER.

Application filed September 15, 1925. Serial No. 56,493.

This invention relates to liquid and gaseous fuel burners, the primary object of the invention being to provide a burner that will efficiently burn and transform heavy oil such as crude oil or the like into a vapor.

An important object of the invention is to provide a burner of this type wherein the burner will become heated by the burning oil, to the end that oil contacting with the heated portion of the burner will become vaporized to burn readily.

A still further object of the invention is to provide a corrugated cap against which the vapor contacts to the end that a highly efficient mixing chamber is produced by the cap.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is a plan view of a burner constructed in accordance with the invention, a portion thereof being broken away.

Figure 2 is a side elevational view thereof.

Figure 3 is a sectional view taken on line 3-3 of Figure 2.

Figure 4 is a sectional view taken on line 4-4 of Figure 1.

Figure 5 is a fragmental bottom plan view of the burner dome.

Referring to the drawings in detail, the reference character 5 indicates the body portion of the burner which is preferably circular in plan and hollowed out to provide an air-passageway through the central portion thereof.

Forming a part of the body portion are vertical tubes 6 that communicate with an oil reservoir 7 disposed at the lower ends thereof, the tubes being arranged in circular formation there being provided spaces 8 between the tubes to allow air to pass therethrough.

As shown, the upper edges of the tubes 6 are inclined as at 9 so that liquid passing

into the reservoir 7 and upwardly through the tubes 6 may overflow into the pan 10 which is in the form of a depression provided in the upper portion of the body portion 5.

Communicating with the reservoir 7 is a feed pipe 11 through which oil from a suitable source of supply may pass into the reservoir 7 to feed the burner. Disposed above the burner proper is a dome or cap 12 which is concavo-convex, the concaved surface thereof being corrugated as at 13 to increase the heating surface thereof. Arms 65 indicated at 14 are formed integral with the dome 12 and extend outwardly and downwardly where they are provided with cut out portions to be fitted over the upper edge of the body portion, to the end that the dome 12 is supported in spaced relation with the upper portion of the body.

Baffle points indicated at 15 are arranged in spaced relation with each other throughout the pan 10, which baffle points become heated and aid in the vaporization of the fuel. From the foregoing it will be obvious that as fuel is fed to the reservoir 7 and passes upwardly into the pipes 6, the same becomes heated and vaporizes, passing upwardly under the dome 13 where it minglest 75 with air passing through the central portion of the burner from where the fuel is spread and passes to the outer edge of the hood or cap 12 where it is burned.

Thus it will be seen that due to this construction, the flame which is produced at the periphery of the hood or cap 12 is circular in formation, resulting in an even heat being produced throughout the area of the burner.

It is of course understood that the initial heating of the burner is accomplished by placing a small quantity of fluid in the pan 10 which may be lighted to heat the hood and upper extremities of the tubes 6.

We claim:

In a burner, a hollow body portion having a central opening and having a trough formed in the upper surface thereof, a reservoir disposed in the hollow body portion 100 and having spaced pipes extending upwardly from the reservoir, the upper ends of the pipes being inclined and lying in a plane with the trough, a cap supported above the

body portion in spaced relation therewith and directly above the pipes, the cap being provided with a corrugated under surface defining grooves to direct fuel downwardly to the trough, and the spaces between the pipes adapted to admit air to the upper ends of the pipes.

In testimony that we claim the foregoing as our own, we have hereto affixed our signatures.

HENRY SMOYER.
WILLIAM H. CUMMING.
HERBERT W. THIELE.
